(57) **CLAIM**

The ornamental design for a menstrual applicator, as shown and described.

DESCRIPTION

FIG. 1 is a perspective view of a menstrual applicator showing our new design;

FIG. 2 is a first side elevation in view thereof;

FIG. 3 is a second side elevation in view thereof;

FIG. 4 is a third side elevation in view thereof;

FIG. 5 is a fourth side elevation in view thereof;

FIG. 6 is a top plan view thereof, shown at an enlarged scale; and,

FIG. 7 is a bottom plan view thereof, shown at an enlarged scale.

The broken lines shown in the drawings are included for the purpose of illustrating portions of the menstrual applicator that form no part of the claimed design.

1 Claim, 7 Drawing Sheets
